CLAIM

The ornamental design for a cleaning tool for a food slicer, as shown and described.

DESCRIPTION

FIG. 1 is a left, top, front perspective view of an embodiment for our design for a cleaning tool for a food slicer;

FIG. 2 is a left side view thereof;

FIG. 3 is a right side view thereof;

FIG. 4 is a front view thereof;

FIG. 5 is a rear view thereof;

FIG. 6 is a top view thereof;

FIG. 7 is a bottom view thereof;

FIG. 8 is a left, top, rear perspective view of another embodiment of our design for a cleaning tool for a food slicer;

FIG. 9 is a left side view thereof;

FIG. 10 is a right side view thereof;

FIG. 11 is a front view thereof;

FIG. 12 is a rear view thereof;

FIG. 13 is a top view thereof; and,

FIG. 14 is a bottom view thereof.

The broken lines in the figures depict portions of the cleaning tool for a food slicer that form no part of the claimed design.

1 Claim, 6 Drawing Sheets
